UNITED STATES PATENT OFFICE.

JACOB E. NEAHR, OF NEW YORK, N. Y.

MATCH-IGNITING DEVICE.

1,104,699.

Specification of Letters Patent.

Patented July 21, 1914.

Application filed September 30, 1913. Serial No. 792,564.

To all whom it may concern:

Be it known that I, JACOB E. NEAHR, a citizen of the United States, residing in the city, county, and State of New York, have 5 invented certain new and useful Improvements in Match-Igniting Devices, of which the following is a specification.

This invention relates to match-igniting devices of the class in which a strip of igniting material is carried in a container in such 10 a manner that an end portion of the strip lies upon the exterior of the container, so that a match may be ignited thereon; the strip being usually chemically prepared, or 15 simply roughened.

The improvements relate principally to the container for the igniting strip, and to the method of inserting, adjusting and holding the strip for use.

20 Certain of the objects of the invention are to simplify and reduce the expense of manufacture of the device; to simplify the manipulation of the strip; to avoid the necessity of frequent re-adjustment of the strip; to 25 provide simple means for holding the strip from disarrangement; and to provide improved means for rendering the interior of the container accessible for insertion of the strip, which is usually in the form of a coil.

30 In carrying out the present improvements, the igniting strip is wound upon a drum and then fastened, preferably by clamping the end of the wound portion against the drum itself; the reserved portion of the strip being 35 coiled within the drum, to be drawn out through an eye as required. This drum may take the place of the box or casing illustrated in U. S. Patent No. 1,040,236, granted to me October 1, 1912, that is, the drum may 40 be mounted upon a base, the latter preferably having the form of an ash tray; and a match-containing pocket may surmount the drum. The invention, however, is not limited to the combination of the drum with 45 an ash tray and pocket.

Other objects and advantages will herein-after appear.

In the accompanying drawings, Figure 1 is a central sectional elevation of a structure 50 including my improvements, which in this example of the invention are shown as mounted upon an ash-tray base and surmounted by a match pocket. Fig. 2 is a perspective view of the strip-containing 55 drum, showing a strip wound thereon, and the surplus portion of the end of the strip

as being torn off. Fig. 3 is a part sectional plan of the drum, showing both the cover and the interior thereof. Fig. 4 is a sectional elevation to illustrate one manner in which 60 the clip may clamp the igniting strip against the surface of the drum, and also lock the cover thereon. Fig. 5 is a view similar to Fig. 4, but illustrating a different form of spring for holding the strip clip closed. Fig. 65 6 is a perspective view of the strip-clamping clip. Fig. 7 is a perspective showing another method of securing the cover on the drum.

The match-igniting strip 1 is usually in 70 the form of a coil, which is dropped into a drum, casing or box 2. This may comprise both a bottom 3 and a body portion 4, the latter forming the sides of the drum. This body portion is preferably cylindrical, although the invention is not limited to a cylindrical form of drum.

The end of the igniting strip 1 is led out 75 through an eye 5, which is cut in the side of the drum. This eye preferably does not extend to either the top or the bottom thereof, so that the wall is not unduly weakened. The strip is pulled out through the eye and wound once around the periphery of the drum, as at 1^a, Fig. 3, thus giving ample 80 exposure of strip upon which to strike the matches; so that the device will serve a long time before it becomes necessary to throw out a fresh length of strip from the drum.

The leading end portion 1^b of the wound 90 strip is drawn out far enough to overlap the portion thereof near the eye 5, Figs. 3 and 4; and a clip 6 clamps both said portions against the body 4 of the drum, preferably in the vicinity of said eye; whereby endwise 95 displacement in either direction of the wound portion of the strip under the pull or friction of the match thereon is prevented; sidewise disarrangement of the strip being also prevented by top and bottom 100 flanges 7 and 8 between which the body 4 is arranged; said eye 5 preferably disposed between said flanges, and said flange 8 being preferably an extension of the bottom 3 of the drum. The clip 6 may be pivoted at 9 105 in ears 10 under the drum; and it may be held firmly in closed position by a leaf spring 11, which is preferably formed by cutting slits 12 inwardly from the edge of the bottom plate 3, as at Fig. 3. This spring 110 normally bears down against an edge 13 of a part of the clip 6 which extends inwardly

from the pivot 9, so as to force the clip 6 inwardly to clamp the strip-portions against the drum. The holding power of the clip may be augmented by one or more points 5 13^a, which may penetrate or indent the strips; and perforations 13^b may be formed in the drum to receive said points and give the clip a still better grip on the strip. The clip has at its upper end a finger piece 14; 10 and by means thereof it may be pulled down to the dotted-line open position at Fig. 4 to release the strip.

The cover 15 of the drum is made movable, to give access to the interior thereof, 15 for inserting the coil of igniting strip. At one side, it may have a tongue 16 to enter a socket 17 in the drum; and at the other side it may have a depending lip 18, provided with a socket 19 in which fits a locking-pin 20 provided upon the upper portion of said clip 6; so that the latter may not only hold the strip, but may also lock the cover onto the drum. The cover is preferably provided with a match-pocket 21, and the drum 25 may have a screw-stem 22 to secure it upon a standard 23 rising from a base 24, which may be an ash tray.

In using the device, the clip 6 may be thrown down to the dotted line position, 30 Fig. 4, thus unlocking the cover 15, which may be removed, and the coil of strip 1 may be inserted in the drum and one end thereof passed out through the eye 5. The cover may be then replaced, and the strip drawn 35 entirely around the drum and past said eye 5. Then the clip 6 may be restored to the Fig. 4 position, to clamp the strip and also lock the cover. Then the surplus end of the strip may be torn off as at Fig. 2; the 40 edge of the clip 6 at 25 serving as a knife-edge to facilitate tearing off the strip. After the exposed portion of the strip is used up, the clip 6 may be again dropped, and enough fresh strip pulled out of the 45 drum through the eye 5 to complete a fresh winding around the same, whereupon the clip may be restored and the worn-out portion of the strip torn off.

One of the advantages of the present 50 structure is that the length of exposed strip may be unlimited except by the circumference of the drum or safe. This makes a match-igniting device nearly all portions of whose circumference are usable for 55 striking matches, and hence the strip will last very long before needing to have a fresh portion drawn out from the drum. The drum is usable in substantially any portion of its circumference, so that the user does 60 not need to turn it around in order to find the match-striking surface. In adjusting the strip, it is only necessary to pull the end of the strip out and wind it around the drum and close the clamp. At any time the 65 drum may be opened without disturbing the

strip. There is no need to open the drum in order to adjust the strip. The body of the drum may consist of a single piece in annular or other hollow form, to contain the coil of strip.

It will be noted that the strip is not all contained within the drum or safe, as in Patent 753,297 granted to me March 1, 1904. Instead of threading the leading end of the strip between a retainer and the inner wall 75 of the drum, as in said patent, my present improvements provide for winding the strip directly around the drum as the strip is paid out through the eye of the drum. The strip, according to the present invention, 80 can be exposed around the entire circumference of the drum, except for the very small space occupied by the clip. Moreover, that portion of the strip which winds around the drum is exposed for its entire 85 width, thus conducing to economy as well as making the exposed portion of the strip last longer before being re-adjusted. In re-adjusting the strip, it is only necessary to open the clip, which renders the tip of the 90 strip readily accessible, and then the strip is easily pulled around the drum, having only one surface to rub against; or, if desired, the strip may be unwrapped from the drum, then pulled out from the eye, then 95 re-wrapped upon the drum, then clipped and the end torn off. Moreover, the backing for the strip is solid all around the drum.

At Fig. 5, the clip spring, instead of being formed from the bottom of the box, is 100 made separately as at 26, and fastened in the top portion of the standard 23. This form of spring would be especially serviceable in case the bottom of the drum is made of wood or other material than spring metal. 105 At Fig. 7 the clip 6 is not provided with a locking pin, but is itself fitted into a locking notch 27 formed in the edge of the cover; the clip also having a projection 28 to catch over the edge of the cover at said notch. 110 This may be substituted for the locking pin seen at the other figures of the drawing.

In cases where it is not desired to detach the cover, the same may be swiveled to the drum to swing sidewise, as at Fig. 7; a pintle 29 extending downwardly from the side of the cover opposite to the clip 6, and having pivotal bearings in upper and lower lugs or straps 30 punched in from the side of the drum. When the clip 6 is swiveled 120 down, the cover may be swung to one side upon said pintle, to give access to the interior of the drum.

Other variations may be resorted to within the scope of the invention, and portions 125 of the improvements may be used without others.

Having thus described my invention, I claim:

1. A match igniter comprising an igniting 130

strip, a strip-containing drum around whose exterior the igniting strip is wound, said drum provided with an eye through which the strip is drawn out to wind around said drum, a cover for said drum, said cover hinged to said drum to swing to one side, and a device for both fastening said cover in closed position and securing the tip of the wound strip, said cover having a notch, and said fastening device locking into said notch, and also having a clip to catch over the cover at said notch and hold the cover down.

2. In a match-igniter, the combination with a match-igniting strip, of a drum containing the same and comprising a body, said body having an eye through which the strip emerges, and mounted to afford a fixed support upon which to wind the strip as the latter pays out of said eye, and means mounted on said drum adjacent to said eye and movable relatively to said body to clamp upon the exterior of said drum both ends of the exposed portion of said strip.

3. In a match-igniter, the combination of a drum, a match-igniting strip contained in the drum, said drum provided with an eye through which the strip emerges, said strip wound entirely around the circumference of the drum, and the tip of the strip overlapping the exposed or withdrawn portion thereof which is adjacent to said eye, and a clip to hold both the tip of the wound strip and also that portion of the strip which is overlapped by said tip.

4. A match-igniting device comprising a strip-containing drum, said drum including a complete single-piece hollow body completely surrounding said strip and provided with an opening through which the strip may be drawn out and wound around the exterior of said body while paying out of said opening, and means exterior to said body and mounted for movement relatively thereto, for securing the wound portion of the strip against endwise displacement.

5. A match-igniting device comprising a drum, said drum including a base and a body portion to inclose the match-igniting strip, said body portion having an opening through which the strip can be drawn out, and said body portion being mounted on said base to afford a fixed support upon which to wind the strip as it pays out through said opening, and releasable means mounted for movement independently of said body, for securing the wound portion of the strip against endwise displacement.

6. A match-igniting device comprising a strip-containing drum, said drum including a complete single-piece hollow body completely surrounding said strip and provided with an opening through which the strip may be drawn out and wound around the exterior of said body while paying out of

said opening, and means exterior to said body and mounted for movement relatively thereto, for securing the wound portion of the strip against endwise displacement; said drum being provided with a cover, and provision being made for relative movement between the cover and said body, to give access to the interior of the drum.

7. A match-igniter comprising an igniting strip, a drum around substantially the entire circumference of which is wound a portion of said igniting strip, said wound portion of said strip being exposed for its entire width, and a reserve portion of said strip extending within the drum; said cover or top closure for said drum; said cover movable to give access to the interior of the drum; and means mounted for movement relatively to said drum to secure the exposed length of strip.

8. A match-igniter comprising an igniting strip, a drum around substantially the entire circumference of which is wound a portion of said igniting strip, said wound portion of said strip being exposed for its entire width, and a reserve portion of said strip extending within the drum, and a cover or top closure for said drum; said cover movable to give access to the interior of the drum, and provided with a match-containing pocket; and means mounted for movement relatively to said drum to secure the exposed length of strip.

9. A match-igniter comprising an igniting strip, a strip-containing drum around whose exterior the igniting strip is wound, said drum provided with an eye through which the strip is drawn out and wound around said drum, the full width of the strip being exposed on the drum, a cover for said drum, said cover movable to give access to the interior of the drum, and a single part mounted to both fasten said cover and secure the tip of the wound strip.

10. A match-igniter comprising an igniting strip, a strip-containing drum around whose exterior the igniting strip is wound, the full width of the strip being exposed on the drum said drum provided with an eye through which the strip emerges, a cover for said drum, said cover movable to give access to the interior of the drum, and a clip mounted to clamp the wound strip against the drum, said clip provided with means for locking the cover upon the drum.

11. A match-igniter comprising an igniting strip, a strip-containing drum around whose exterior the igniting strip is wound so that one end of the exposed portion of the strip overlaps the other end of said exposed portion, said drum provided with an eye through which the strip is drawn out, a cover for said drum, said cover movable to give access to the interior of the drum, a spring clip mounted upon the drum in the

vicinity of said eye and movable to clamp against the drum the overlapped ends of the exposed portion of the wound strip, and means upon said cover to coöperate with 5 said clip to lock the cover.

12. A match-igniter comprising a base, an igniting strip, a strip-containing drum around whose entire exterior the igniting strip is wound, said drum mounted on said 10 base and provided with an eye through which the strip is drawn out to wind around the drum, a clip mounted upon the drum to clamp the tip of the wound strip to the drum, a cover for said drum; said cover 15 movable to give access to the interior of the drum, and a match-containing pocket on said cover.

13. A match-igniter comprising an igniting strip, a strip-containing drum around 20 whose exterior the igniting strip is wound, said drum provided with an eye through which the strip is drawn out to wind around said drum, a cover for said drum, and a part mounted upon said drum and movable relatively thereto for both fastening said cover and securing the tip of the wound strip; said cover having a tongue-and-socket connection with said drum to permit the cover to be detached after unlocking thereof. 25

14. In a match-igniter, the combination 30 of an igniting strip, a strip-containing drum around whose exterior the igniting strip is wound, said drum provided with an eye through which the strip is drawn out and wound entirely around the drum, one end overlapping the other end of the exposed portion of the strip, and the strip being exposed for its full width upon said drum, and a clip to hold both the tip of the wound or 35

exposed strip and also that portion of the 40 wound strip which is overlapped by said tip; said clip provided with means to indent or penetrate the strip.

15. A match-igniter comprising an igniting strip, a strip-containing drum around 45 whose exterior the igniting strip is wound, said drum provided with an eye through which the strip is drawn out to wind around said drum, a cover for said drum, said cover hinged to said drum to swing to one side, and a device for both fastening said cover in 50 closed position and securing the tip of the wound strip.

16. A match-igniter comprising a match-igniting strip, a strip-containing drum 55 around whose exterior the igniting strip is wound, said drum provided with an eye through which the strip is drawn out to wind around said drum, a cover for said drum, said cover hinged to said drum to 60 swing to one side, and a device mounted upon the drum for securing the tip of the wound strip; said cover having a notch, and said securing device locking into said notch, to fasten the cover. 65

17. A container of the class described, comprising a cover, a bottom, and an intervening entire hollow body inseparably fixed to the bottom, said cover movable to give access to the interior of the container, said body having an eye, and a clip to coöperate with the exterior surface of the body near 70 said eye, said clip mounted for releasing movement away from said body.
